UNITED STATES PATENT OFFICE.

RUFUS J. SCHROCK, OF LOGANTON, PENNSYLVANIA.

TRACE-HOOK.

1,157,185.

Specification of Letters Patent.

Patented Oct. 19, 1915.

Application filed May 3, 1915. Serial No. 25,532.

To all whom it may concern:

Be it known that I, RUFUS J. SCHROCK, a citizen of the United States, residing at Loganton, in the county of Clinton and State of Pennsylvania, have invented a new and useful Trace-Hook, of which the following is a specification.

The device forming the subject matter of this application is a trace hook and one object of the present invention is to provide a novel form of latch which forms a bridge between the bill of the hook and the shank of the connector.

Another object of the invention is to provide novel means whereby the latch is held in place and adjusted readily.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing:—Figure 1 shows the invention in side elevation, parts being broken away, the latch being in one of its locked positions; Fig. 2 is a fragmental side elevation wherein the latch is disposed in another of its locked positions; Fig. 3 is a fragmental side elevation showing the manner in which the latch is manipulated during the mounting thereof; Fig. 4 is a cross section on the line 4—4 of Fig. 1; Fig. 5 is a cross section on the line 5—5 of Fig. 1; Fig. 6 is a top plan of the latch.

The trace hook forming the subject matter of this application embodies a shank 1 of any desired length provided with attaching holes 2 and terminating in a hook 3, the bill of which is denoted by the numeral 4, one edge of the bill being beveled as indicated at 5, adjacent the free end of the bill. Mounted in the shank 1 at the point where the shank merges into the hook 3 is a transverse projection 6 which may be in the form of a fixed pin.

The invention comprises a latch denoted by the numeral 7 provided at one end with a socket 8 mounted to slide on the bill 4.

Adjacent its opposite end, the latch 7 is provided with spaced wings 9 which lie on opposite sides of the shank 1 as Fig. 5 will clearly disclose. In the wings 9 longitudinal slots 10 are formed, the same being adapted to receive the projection 6. In their edges, the wings 9 are equipped with mouths 11 which communicate with the slots 10.

Referring to Figs. 1 and 2 it will be observed that no matter in which end of the slots 9 the projection 6 happens to be lodged, accidental displacement of the latch from the projection will be avoided.

In order to adapt the structure to receive a trace, the latch 7 is moved longitudinally until the projection 6 lies opposite to the mouths 11. Then the latch 7 is lifted slightly permitting the projections 6 to pass outwardly through the mouths 11, the beveling of the bill 4 indicated at 5 permitting such an operation. Then, the latch 7 is slid to the right, referring to Fig. 1, whereupon the necessary connection may be made. Subsequently, the latch 7 is moved to the left, the projection 6 is entered in the slots 10 through the mouths 11, and the latch 1 is moved longitudinally in one direction or in an opposite direction, until the projection 6 is engaged in one end or the other of the slot, as shown in Fig. 1 or as shown in Fig. 2. The mounting of the latch 7 will be understood readily from Fig. 3, the free end of the bill 4 being inserted into the socket 8 and the latch 7 being swung downwardly until the projection 6 enters the slots 10 through the mouths 11.

The foregoing description relates to the initial mounting of the latch in position, and it will be understood that during the manipulation of the device to effect a connection of the trace it is not necessary to swing the latch 7 into the extreme position of Fig. 3.

Having thus described the invention, what is claimed is:—

1. A trace connector comprising a shank terminated in a hook having a bill; a transverse projection on the shank; and a latch slidable longitudinally of the bill, the latch comprising a socket receiving the bill, and wings located on opposite sides of the shank, one wing having a longitudinal projection-holding slot and being provided in its edge with a projection-receiving mouth communicating with the slot.

2. A trace connector comprising a shank terminated in a hook having a bill; a trans-

verse projection on the shank and a latch
slidable longitudinally of the bill, the latch
comprising a socket receiving the bill, and
wings located on opposite sides of the shank,
5 one wing having a longitudinal projection-
holding slot and being provided in its edge
with a projection-receiving mouth communi-
cating with the slot, the inner edge of the
bill being beveled at its edge to permit the

projection to pass through the mouth when 10
the latch is tilted.

In testimony that I claim the foregoing as
my own, I have hereto affixed my signature
in the presence of two witnesses.

RUFUS J. SCHROCK.
